GAME BOARD

Carroll B. Mallonee, Star Rte. 1, Box 107,
Lacomb, Oreg. 97354

Filed Mar. 13, 1967, Ser. No. 6,195

Term of patent 14 years

(Cl. D34—5)

FIG. 1

I claim:

The ornamental design for a game board, substantially as shown.
